Primary Examiner — Rosemary K Tarcza(57) **CLAIM**

The ornamental design for a battery pack, as shown and described.

DESCRIPTION

FIG. 1 is a perspective view of a battery pack as seen from the front, bottom, and left side;
FIG. 2 is a front view thereof;
FIG. 3 is a back view thereof;
FIG. 4 is a right side view thereof;
FIG. 5 is a left side view thereof;
FIG. 6 is a top end view thereof; and,
FIG. 7 is a bottom end view thereof.

The dotted line portions of the drawings represent environmental structure only and do not form part of the claimed design.
